CLAIM

The ornamental design for a stand, as shown and described.

DESCRIPTION

FIG. 1 is a perspective view of a stand showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is bottom plan view thereof; and,

FIG. 8 is a schematic of a usage state of an embodiment.

The broken lines in FIGS. 3 and 6 are for the purpose of illustrating the environment of the article only and form no part of the claimed design.

1 Claim, 5 Drawing Sheets

FIG. 1

FIG. 2

FIG. 3

FIG. 5

FIG. 4

FIG. 6

FIG. 7

FIG. 8
